(57) **CLAIM**

The ornamental design for a wearable seating cushion, as shown and described.

DESCRIPTION

FIG. 1 is a front perspective view of a wearable seating cushion, showing our new design;

FIG. 2 is a front elevational view thereof;

FIG. 3 is a left side elevational view thereof; whereas the right side elevational view is a mirror image;

FIG. 4 is a rear elevational view thereof;

FIG. 5 is a top plan view thereof;

FIG. 6 is a bottom plan view thereof;

FIG. 7 is a left side, rear perspective view thereof, shown in use; and,

FIG. 8 is a right side elevational view thereof, shown in use. The broken lines shown in the drawings are for illustrative purposes only and form no part of the claimed design.
